AUTOMOBILE WHEEL COVER

William M. Brownlie, Dearborn, Mich., assignor to Chrysler Corporation, Highland Park, Mich., a corporation of Delaware

Application March 31, 1959, Serial No. 55,283

Term of patent 7 years

(Cl. D14—30)

I claim:

The ornamental design for an automobile wheel cover, substantially as shown.
